UNITED STATES PATENT OFFICE.

WILLIAM T. MESSINGER, OF BOSTON, MASSACHUSETTS.

FASTENING DEVICE.

SPECIFICATION forming part of Letters Patent No. 604,408, dated May 24, 1898.

Application filed May 24, 1897. Serial No. 637,904. (No model.)

To all whom it may concern:

Be it known that I, WILLIAM T. MESSINGER, of Boston, county of Suffolk, and State of Massachusetts, have invented an Improvement in Fastening Devices, of which the following description, in connection with the accompanying drawings, is a specification, like letters and figures on the drawings representing like parts.

- 10 The present invention relates to a fastening device mainly intended for a necktie-faster, the object being to provide a device which will prevent the necktie from riding up the side of a stand-up collar, the device embodying the invention being so constructed that it will keep the tie down preferably just below the edge of the collar, so as to cover the part where the collar adjoins the shirt and at the same time hold the tie flat, while 15 it is impossible for any part of the device to be visible when the tie is adjusted. Devices which have been heretofore designed for this purpose have been arranged to coöperate with the shirt-stud or collar-button, and are 20 objectionable not only for the reason that it is difficult to properly attach them, but also because the necktie does not properly cover the fastening device to prevent its frequent exposure to view.
- 25 The object of the present invention is to provide a fastening device which can be readily attached to any tie and after it is once attached cannot by any possibility become accidentally detached, the said fastening device being so arranged that the main portion thereof will be wholly covered by the material of which the tie is made, the only part which is exposed being the hook or portion which is adapted to slip under the edge of the 30 collar, so that it is impossible to expose the device after the tie is once placed in position.
- In carrying out the invention the fastening device is formed, preferably, of a single piece having a tongue or projection adapted to form 35 a hook to slip under the edge of a collar and a coöoperating portion also constituting a retaining device substantially parallel with said hook, the said coöoperating portion being provided with a pointed end adapted to be 40 inserted between the back or lining portion of the tie and the front or outer portion thereof, and the entire coöoperating portion which
- is provided with the said point is of such shape that it can be caused to follow the point through the opening made thereby until it 55 lies wholly between the front and back layers of material which form the tie, so that only the hook is on the outside of the material. The said coöperating portion is preferably so constructed as to extend upward to 60 a point substantially adjacent to the top of the hook and downward somewhat below the throat of the same, so that the lower edge of the coöperating portion will engage within the tie with the crease between the inner and 65 outer layers of material, while the throat of the hook will project from the inner layer at a point somewhat above the said crease. Thus when the hook is placed in position the collar will be engaged between the same 70 and the coöperating portion within the tie, the throat of the hook coming up against the lower edge of the collar to prevent the tie from rising, while the lower portion of the tie is held flat and somewhat below the edge of 75 the collar by the lower part of the said coöperating portion, which is hidden by the material of which the tie is formed, and the upper part of said coöperating portion within the tie will hold the tie flat against the collar parallel with the tongue of the hook, preventing any possibility of its turning downward or otherwise away from the collar. The said coöperating portion within the tie, moreover, preferably has a considerable lateral extent, and the lower edge thereof may be flattened for some distance, so as to lie along the 80 crease of the tie and prevent the device from turning or tipping laterally.
- The device may also be so constructed that 90 when attached to the tie it will not be readily detached therefrom, this being preferably accomplished by providing the said coöperating portion, which lies within the tie, with a shoulder adapted to be engaged by the material 95 after it has passed through the same, the whole device thus being snugly held in position.
- Figure 1 is a front elevation of a device embodying the invention. Fig. 2 is a similar 100 view of the device applied to a tie, the part which lies between the face and lining of the tie being shown in dotted lines, while the hook, which is outside, is shown in full lines. Fig.

3 is an elevation of the device, taken at right angles to the position shown in Fig. 2 and applied to the tie, which is shown in section. Figs. 4, 5, and 6 are front elevations of the device in different positions, showing the manner of applying the same to the tie. Fig. 7 is a section on line x^6 of Fig. 2, looking toward the left; and Fig. 8, a similar section on the same line, looking toward the right, Figs. 10 7 and 8 being on a larger scale than the others.

The hook a and the coöperating portion a^2 , which, in conjunction with the hook, is adapted to hold the tie snugly against the collar, are herein shown as formed of a single blank, 15 there being a neck a^3 , Figs. 6 and 7, between the hook proper and the body of the coöperating portion, which is adapted to be bent substantially at a right angle to the said hook and the coöperating portion, so as to offset 20 the hook to form the throat portion thereof, the said throat portion being adapted to engage the lower edge of the collar and to pass through the material of which the tie A is formed when the device is in position, with 25 the hook outside of the tie and the coöperating portion inside thereof, or between the material which forms the face of the tie and that which forms the lining thereof.

The coöperating portion aforesaid, which is 30 adapted to be covered by the material which forms the tie and which also constitutes the retaining portion to keep the device attached to the tie, may be constructed in any suitable way, but should be in the form of a rod or 35 strip curved to the desired shape and terminating in a point, so that when the said point is caused to penetrate the material the remainder of the said portion can follow the point through the material until substantially 40 the entire retaining portion is within the tie up to the point where the hook proper is connected therewith, the said hook then being the only part of the device which is exposed at the outside of the tie, the material of which 45 is substantially intact except for the small hole through which the retaining portion has been passed and through which extends the neck or connecting portion between the hook and the retaining device, the latter thus also 50 constituting a support for the tie to hold the same snugly against the surface of the collar and to keep it flat.

As shown in the drawings, the portion a^2 55 comprises a loop 2, extending laterally from the hook a , the lower member of the said loop then extending in the opposite direction to a point at the opposite side of the said hook and then curving upward and terminating in the point 3 substantially adjacent to the top 60 of the hook a . To insert the device, the point 3 is passed through the back or lining of the tie, as shown in Fig. 4, so as to pass between the said lining and the front or outer material of the tie, the point being inserted as shown 65 in dotted lines, Fig. 4, and the device turned and pushed inward until it reaches the position shown in Fig. 5. The rounded end of

the loop 2 is then worked downward through the opening until the upper portion of the loop enters the same, as shown in Fig. 6, after 70 which the device is pushed to the right, Fig. 6, until it reaches the position shown in Fig. 1, the throat a^3 passing through the material where the point 3 originally penetrated it.

As herein shown, the loop 2 is provided 75 where it adjoins the hook a with a shoulder 20, over which the material slips when the device is pressed into its final position, so that it is practically impossible to accidentally displace the fastening device after it is once applied to the tie. The said shoulder is shown as rounded, and the lower edge of the loop where it adjoins the throat a^3 is also shown as rounded, so that while the shoulder will effectively prevent the accidental removal of 85 the device the user can remove the same without difficulty by lifting the material, as with a knife or pin, over the shoulder without having the material catch or tear.

As herein shown, the loop 2 is extended below the bottom of the hook, this construction being preferable for the reason that the lower edge of the tie is thereby carried downward somewhat below the edge of the collar, so that it will cover the said lower edge, it being ob- 90 viously impossible, moreover, after the device is once placed in position to expose any portion of the same, since the outer support for the tie is wholly hidden within the material, while the hook proper is behind the collar, 95 the lower portion of the loop, moreover, preventing the lower edge of the tie from being turned up, so as to expose even the portion a^3 of the device, which connects the hook with its coöperating portion. 100

By elongating and flattening the loop, as shown, a bearing is given for the same along the lower edge inside of the tie, so that the device is maintained at a right angle to the edge of the tie, as shown, making it practically impossible for the device to tip in either 110 direction. 105

While the construction herein shown and described as illustrative of the invention is believed to be the most practicable form of 115 device for the purpose, it is not intended to limit the invention to this specific construction, since many modifications may be made without departing from the invention. Furthermore, it is not intended to limit the invention to a device for fastening neckties alone, since substantially the same device 120 may be useful for other purposes, such, for example, as fastening belts and the like. 125

I claim—

1. In a fastening device, the combination with a hook, of a coöperating portion, an offset portion connecting the said hook and coöperating portion, said offset portion being adapted to extend through an opening in the 130 material to which the fastening device is connected and being joined to the coöperating portion between the upper and lower edges thereof, substantially as described.

2. In a fastening device for neckties, the combination with a hook, of a coöperating portion lying in a plane substantially parallel to that of the said hook, the lower edge of said coöperating portion being adapted to engage the crease at the edge of the tie within the material of which the tie is made, an offset connecting portion between the hook and coöperating portion adapted to pass through the said material, the said offset portion forming the throat of the hook and joining the coöperating portion below the top thereof whereby the fastening device is held in position by the engagement of the coöperating device with the crease, and the engagement of the offset portion with the material at the opening through which it passes, while the hook and coöperating member both extend from the throat of the hook in the same direction at opposite sides of the material, substantially as described.

3. A necktie-fastening device comprising a hook adapted to engage a collar, and a retaining device for securing the hook to the tie and adapted to hold the tie against the side of the collar, the said retaining device comprising a loop extending laterally from one side of the said hook, the end of said loop extending to the opposite side of the hook and terminating in a point adapted to penetrate the material of which the tie is made, substantially as described.

4. A necktie-fastening device comprising a hook adapted to engage a collar, and a retaining device for securing the hook to the tie and adapted to hold the tie against the side of the collar, the said retaining device comprising a loop extending laterally from one side of the said hook, the end of said loop extending to the opposite side of the hook and terminating in a point adapted to penetrate the material of which the tie is made, and a shoulder on said retaining device adjacent to the point of connection between said retaining device and said hook, substantially as described.

5. A necktie-fastening device comprising a hook adapted to engage one side of the collar and a retaining device adapted to secure the hook to the tie and hold the tie against the side of the collar, the said retaining device comprising a loop extending laterally from one side of the hook, the end of said loop extending to the opposite side of the hook and

thence around to a point substantially adjacent to the top thereof, the said loop being adapted to be wholly inserted between the face and lining of the tie and thereby constitute an invisible retaining device for the hook, substantially as described.

6. The combination with the hook a , provided with the coöperating member a^2 which also constitutes a retaining device, said member a^2 comprising a loop 2 terminating in a point 3 substantially adjacent to the top of the said hook, the connecting portion a^3 between said hook and said loop, and the shoulder 20 at the upper side of said loop adjacent to the hook, substantially as and for the purpose described.

7. The herein-described fastening device for a necktie comprising a hook and a coöperating member lying in a plane substantially parallel with that of the hook, the said coöperating member being adapted to lie between the layers of material of which the tie is formed, the lower edge of said coöperating member being below the throat of the hook and extending laterally beyond the same in a substantially straight line to engage the crease at the edge of the tie and hold the same below the edge of the collar and at the same time to maintain the hook substantially perpendicular to the edge of the tie, substantially as described.

8. The herein-described fastening device for a necktie comprising a hook and a coöperating member lying in a plane substantially parallel with that of the hook, the said coöperating member being adapted to lie between the layers of material of which the tie is formed, a throat portion extending from the hook proper to the coöperating member, the said throat portion being adapted to extend through a perforation in the material, and a substantially straight lower edge portion of the coöperating member to engage the crease at the edge of the tie and maintain the hook substantially perpendicular thereto, substantially as described.

In testimony whereof I have signed my name to this specification in the presence of two subscribing witnesses.
